BEDCOVER SUPPORT

Marion B. Orford, Garden City, N. Y.

Application November 20, 1947, Serial No. 787,120

9 Claims. (Cl. 5—319)

1

This invention relates to supports for bed covers and particularly to a bed cover support adapted to hold the bed covers above the feet of an occupant of the bed to keep the covers from contacting the feet particularly when the occupant is lying on his back.

The object of the invention is to provide an improved bed cover support of the character mentioned which may be readily applied to a bed and adjusted to support the covers so as to prevent the covers from resting upon or coming in contact with the feet.

A further object of the invention is to provide a device as mentioned which may be readily and quickly adjusted to be practically unnoticeable, and out of the way when not desired for use, without removing the same from the bed; and which may be as readily adjusted into operative position when needed or desired.

Other objects of the invention are to provide a device as mentioned which shall be of simple construction, of low cost to manufacture, and which may be readily installed on a bed without the use of any tools whatever.

A further object of the invention is to provide a device as mentioned which will not be readily displaced accidentally when in use.

Other objects will appear hereinafter.

With these objects in view, the invention consists generally in a bed cover support comprising a base portion adapted to be positioned at the foot of a bed beneath the end of the mattress and resting on the mattress support which is usually the bed springs, a standard pivotally connected to the base and adapted to be swung laterally of the bed, and a supporting frame member pivotally connected to the standard.

The invention further consists in various details of construction and arrangements of parts as will be fully described hereinafter and particularly pointed out in the claims.

The invention will be more readily understood by reference to the accompanying drawings forming a part of this application and in which:

Figure 1 is a perspective view of a bed cover support embodying my invention and illustrating the device in extended or operative position.

Figure 2 is a detail of the pivotal connection between the supporting frame and the standard, and illustrated upon an enlarged scale.

Figure 3 is a section on the line 3—3 of Figure 2.

Figure 4 is a detail view illustrating the connection between the standard and base.

Figure 5 is a section on the line 5—5 of Figure 4.

2

Figure 6 is a view illustrating the device applied to a bed, and

Figure 7 is a detail view illustrating the device as folded and out of operative position.

Referring to the drawings, the device consists generally in a base 10, standard 11, and a supporting member 12 for holding the bed clothes in an elevated position over the feet.

The base 10 is substantially flat and is adapted to be arranged at the foot of a bed and arranged under the mattress and resting on the mattress support, which is usually the springs, as illustrated in Figure 6 of the drawings, 13 indicating the mattress and 14 the mattress support. The base 10 is preferably formed of a strip of strap metal, preferably aluminum bent forming a comparatively broad inner end 16, converging side portions 17—17 and terminating in inturned abutting ends 18.

Riveted, or otherwise secured to the ends 18, and preferably to the inner faces thereof, is an upwardly extending bracket plate 19 upon which the standard 11 is pivotally mounted.

The standard 11 comprises a straight bar preferably rectangular in cross section and is mounted on the outer or rear face of the bracket plate 19 by means of a pivot pin 20. The pivot pin preferably comprises a shouldered bolt extending through a vertical slot 23 in the bracket plate 19 and threaded into the standard 11 as shown in Figure 5, and head 24 of the bolt having sufficient clearance to permit the bolt to move readily in the slot. Spaced above the pivot bolt 21 is an inwardly extending lock pin 25 which is adapted to engage in a notch 26 in the upper edge of the plate 19 when the standard is perpendicular to the base, and the pivot 20 is at the lower portion of the slot 23.

The cover supporting member 12 is formed of a strip, preferably of metal, bent to a general triangular form, consisting of a broad outer base 27, and converging legs 28 which terminate at the apex of the triangle in a pair of parallel extension lugs 29 spaced apart to receive the upper end of the standard 11 between them.

A bolt 30 extends through a hole 31 in one of the lugs 29, and a hole 32 in the standard, and is then threaded into the other lug 29, as indicated at 33 in Figure 3.

The bolt 30 is arranged slightly forwardly of the center of the standard; and a cross pin 36 is fixed in the lugs 29 so as to engage the upper end of said standard to hold the member 12 in an upwardly and forwardly inclined operative position and to limit the rearward swing thereof to a substantially vertical position to avoid con-

tacting the footboard of the bed. The outer upper edge of the standard is rounded as at 34 to avoid injury to the bed clothes.

In using the device the base 10 is placed beneath the foot of the mattress 13 and rested upon the bed springs or other mattress support. It will be noted that the strip from which the base is formed is vertically disposed edgewise, so that the upper edge will constitute ridges which will become more or less embedded in the under side 10 of the mattress, thereby holding the device from accidental displacement when in use. After the base is in position the standard is swung to vertical position and then moved downwardly with the pin 25 engaging in the notch 26, thereby securing the standard in vertical position. The triangular support 12 is then swung inwardly over the foot of the mattress where it is in position to support the bed covers as illustrated in Figure 6, the dotted line 27 indicating said covers.

When not in use, the device may be folded so as to be substantially unnoticeable, which is done by lifting the standard 11 until the pivot pin 20 engages the upper end of the slot 23 and the pin 25 is disengaged from the notch 26, and then swinging the standard laterally into the position shown in Figure 7; the triangular support 12 having first been raised into substantial alignment with the standard. In this position the device is entirely below the level of the upper surface of 30 the mattress and may be completely concealed from view by the bed covers.

I claim:

1. A bed cover support comprising a base adapted to be positioned under the foot of a mattress, a standard pivotally mounted on said base and adapted to swing laterally thereof interengaging means on said base and said standard for maintaining the latter in raised operative position, and a bed cover supporting member on the upper end of said standard.

2. A bed cover support comprising a base adapted to be positioned under the foot of a mattress, a standard pivotally mounted on said base to swing laterally thereof, cooperating means on said base and said standard for latching the latter in operative position, and a bed cover supporting member on said standard.

3. A bed cover support comprising a base adapted to be positioned under the edge portion of a mattress, a standard pivotally mounted on said base and adapted to swing laterally thereof, interengaging means on said base and said standard for maintaining the latter in operative position and a bed cover supporting member pivotally mounted on said standard.

4. In a device of the class described, a base adapted to be positioned under the edge of a mattress, a bracket plate fixed to said base, said plate having a vertical slot and a peripheral notch in the upper edge thereof, a standard, a pivot pin on said standard slidably mounted in said slot, a latch pin on said standard adapted to engage in said notch when the standard is in operative position, and a bed cover supporting member on 65 said standard.

5. In a device of the class described, a base

adapted to be positioned under the edge of a mattress, a standard pivotally mounted on said base to swing laterally thereof, means for latching said standard in operative position, and a bed cover support pivotally mounted on the upper end of said standard.

6. In a device of the class described, a base adapted to be positioned under the edge of a mattress, a standard supported by said base, a cover supporting frame, a pair of lugs on said frame, a pivot pin extending through said lugs and through said standard adjacent the upper end thereof, the upper end of said standard forming a slip shoulder, a pin fixed in said lugs and adapted to engage said shoulder to hold the supporting frame in an upwardly and forwardly inclined position and to limit the rearward swing thereof to a substantially vertical position.

7. In a device of the class described, a base 20 adapted to be positioned under the edge of a mattress and comprising a strip of strap metal arranged on edge and bent to form a broad inner end, converging side portions, and a narrow outer end, a standard pivotally mounted at the narrow 25 end of said base and adapted to swing laterally thereof, cooperating means on said base and standard for holding the latter in operative position, and a bed cover supporting member on said standard.

8. In a device of the class described, a base adapted to be positioned under the edge of a mattress, said base being tapered from a comparatively broad inner end to a narrow outer end, a standard pivotally mounted at the narrow end 35 of said base and adapted to swing laterally thereof, cooperating means on said base and said standard for holding the latter in operative position, and a bed cover supporting member pivotally mounted on a transverse axis at the upper end of 40 said standard.

9. In a device of the class described, a base adapted to be positioned under the edge of a mattress said base being tapered from a comparatively broad inner end to a narrow outer end, a standard 45 mounted at the narrow end of said base and adapted to swing laterally thereof, cooperating means on said base and said standard for holding the latter in operative position, and a bed cover supporting member comprising a triangular 50 frame, a pivotal connection between the apex of said triangular frame and the upper end of said standard, and means for limiting the swing of said triangular frame on said standard, from an operative supporting position above said base to a position 55 in alignment with said standard.
